[57] CLAIM

The ornamental design for a card badge, as shown and described.

DESCRIPTION

FIG. 1 is a perspective view of my new design of a card badge;

FIG. 2 is a side elevational view of my new design shown in FIG. 1, the opposite side being identical thereto;

FIG. 3 is a top plan view of the card badge showing my new design, the opposite side being identical thereto; and,

FIG. 4 is an end elevational view of my new design shown in FIG. 1, the opposite end being identical thereto.

The broken lines are shown for illustrative purposes only and form no part of the claimed design.
